REFRIGERATION CONTROL SYSTEM

William L. McGrath, St. Paul, Minn., assignor to
Minneapolis-Honeywell Regulator Company,
Minneapolis, Minn., a corporation of Delaware

Application March 17, 1938, Serial No. 196,445

15 Claims. (Cl. 62—4)

This invention relates to control systems for a refrigerating apparatus and more particularly to control systems for accomplishing periodic defrosting of the refrigerating apparatus.

The prime object of this invention is to provide a control system for a refrigerating apparatus wherein the refrigerating apparatus is started and stopped to maintain desired conditions, wherein means are provided for preventing starting of the refrigerating apparatus until defrosting of the evaporator has occurred, and wherein this last mentioned means are rendered operative and inoperative as an incident to operation of the refrigerating apparatus for defrosting the evaporator thereof following a predetermined number of cycles of operation of the refrigerating apparatus.

Other objects and advantages will become apparent to those skilled in the art upon reference to the accompanying specification, claims, and drawing, in which:

Figure 1 illustrates diagrammatically one form of this invention.

Figure 2 is a diagrammatic illustration of another form of this invention.

Referring now to Figure 1 a refrigerating apparatus is generally designated at 9 for maintaining desired conditions such as desired temperature conditions in a space generally designated 10. The space 10 may be a walk-in box, a storage compartment, a room, or any other device in which it is desired to maintain predetermined conditions such as temperature, humidity, etc. An evaporator 11 is located in the space 10 for cooling the same and expanded refrigerant is withdrawn from the evaporator 11 through a suction or low pressure pipe 12 by a compressor 13 operated by a motor 14. The compressor 13 compresses the expanded refrigerant and delivers this compressed refrigerant into a condenser 15 wherein it is liquefied. The liquid refrigerant flows from the condenser into a receiver 16 and then through a liquid line 17 into the evaporator 11 under the control of an expansion valve 18. For purposes of illustration the expansion valve 18 is shown to be a thermostatic expansion valve having a capillary tube 19 and a bulb 20 containing a volatile fluid located adjacent the suction line 12 at the discharge side of the evaporator 11.

The operation of the compressor 13, that is, the starting and stopping of the compressor is controlled by a starter or relay generally designated at 22 and this relay may comprise a relay coil 23 for operating switch arms 24, 25, and 26 with re-

spect to contacts 27, 28, and 29, respectively. Upon energization of the relay coil 23 the switch arms 24 and 25 are moved into engagement with the contacts 27 and 28 and the switch arm 26 momentarily engages the contact 29. Upon de-energization of the relay coil 23, the switch arms 24, 25, and 26 are moved to the right by means of springs gravity or other means, not shown, to cause switch arms 24, 25 to disengage contacts 27 and 28. During right-hand movement of the switch arm 26 the contact is not engaged since a piece of insulating material 30 prevents this, hence the contact 29 is only momentarily engaged by the switch arm 26 when the relay coil 23 is energized.

The starter or relay 22 is controlled primarily by a temperature responsive controller generally designated at 32 which responds to changes in the temperature within the space or box 10. This controller may comprise a bellows 33 containing a volatile fluid for operating a lever 34 against the action of a spring 35. The lever 34 in turn operates a switch 36 having electrodes 37 and 38. Upon an increase in space or box temperature the bellows 33 expands to cause the mercury to bridge electrodes 37 and 38 and upon a decrease in temperature the electrodes 37 and 38 are unbridged. By suitably adjusting the tension in the spring 35 the temperature setting of the controller 32 may be varied at will. For purposes of illustration it is assumed that the mercury switch 36 is closed when the temperature in the box rises to 40° and is opened when the temperature decreases to 38°.

The relay or starter is also controlled by a suction pressure controller generally designated at 40 and this controller may comprise a bellows 41 connected by a pipe 42 to the suction line 12. The bellows 41 operates a lever 43 against the action of a tension spring 44. The lever 43 operates a mercury switch 45 having electrodes 46 and 47. Upon an increase in suction pressure the bellows 41 expands to cause the mercury to bridge electrodes 46 and 47 and upon a decrease in suction pressure the mercury is caused to separate from the electrodes 46 and 47. By suitably adjusting the tension of the spring 44 the pressure setting of the controller 40 may be varied at will. For purposes of illustration it may be assumed that mercury switch 45 closes when the suction pressure rises to some predetermined high value such as 40 lbs. which is indicative of defrosting of the evaporator 11. The switch may open at some lesser value such as 38 lbs. Hence the only time switch 45 closes is when the suction pressure

rises to a high value corresponding to the defrosting temperature of the evaporator 11.

The relay or starter 22 is also controlled by a high pressure cut-out generally designated at 50 and this cut-out may comprise a bellows 51 connected by a pipe 52 to the high pressure side of the compressor 13. The bellows 51 operates a lever 53 against the action of a tension spring 54. The lever 53 operates a mercury switch 55 having electrodes 56 and 57. By suitably adjusting the tension of the spring 54 the pressure setting of the high pressure cut-out 50 may be adjusted at will. For purposes of illustration it is assumed that the switch 55 is opened when the high pressure rises to a predetermined high value such as 180 lbs. and is closed when the high pressure decreases to a predetermined lower value such as 160 lbs.

The relay or starter 22 may also be controlled by an overload cut-out generally designated at 60 and this cut-out may include a resistance heater element 61 located in the compressor circuit for heating the bimetallic element 62. Upon the occurrence of an overload condition in the compressor circuit the bimetallic element 62 is flexed toward the left to allow contacts 63 and 64 to separate. Suitable resetting means, not shown, may be provided for reclosing the contacts 63 and 64. Since such a construction is well known in the art, a further description is not considered necessary.

Power is supplied to the compressor motor 14 and to the control system by means of line wires 66 and 67 leading from some source of power not shown. With the parts thus far described in the positions shown in the drawing the relay or starter 22 is deenergized and the compressor 13 is shut down. Assume now that the suction pressure has risen to 40 lbs. indicating that defrosting of the evaporator 11 has occurred and that the space or box temperature has increased to 40°, the switches 45 and 36 will then be closed to complete a starting circuit from the line wire 66 through contacts 63 and 64 of the overload cut-out 60, electrodes 56 and 57 of the high pressure cut-out 50, electrodes 37 and 38 of the temperature responsive controller 32, electrodes 46 and 47 of the suction pressure controller 40, and relay coil 23 back to the line wire 67. Completion of this starting circuit energizes the relay coil 23 to move the switch arms 24 and 25 into engagement with the contacts 27, 28, respectively. Movement of the switch arm 25 into engagement with the contact 28 completes a load circuit from the line wire 66 through contact 28, switch arm 25, compressor motor 14 and heater element 61 back to the other line wire 67. Completion of this circuit causes operation of the compressor 13.

Movement of the switch arm 24 into engagement with the contact 27 completes a maintaining circuit for the relay coil 23 which is independent of the suction pressure controller 40 and this maintaining circuit may be traced from the line wire 66 through contacts 63 and 64 of the overload cut-out 60, electrodes 56 and 57 of the high pressure cut-out 50, electrodes 37 and 38 of the space or box thermostat 32, contact 27, switch arm 24, and relay coil 23 back to the line wire 67. Completion of this circuit maintains the relay or starter 22 energized until the box temperature decreases to 38°. Accordingly the compressor is placed in operation upon a call for cooling by the box thermostat 32 when the suction pressure controller 40 indicates that defrosting of the evaporator 11 has taken place and

after the compressor has once been placed in operation it is maintained in operation under the control of the box thermostat 32 until the box temperature is decreased to 38°. The overload cut-out 60 and the high pressure cut-out 50 are located in both the starting and maintaining circuits for the starter 22 and therefore the compressor 13 is shut down in case of overload conditions in the compressor circuit and high pressure conditions on the high pressure side of the refrigerating apparatus.

A switch formed by a switch arm 70 and a contact 71 is located in parallel with the electrodes 46 and 47 of the suction pressure controller 40 and when this switch is closed, as is shown in Figure 1, the suction pressure controller 40 is shunted out or rendered inoperative whereby the relay or starter 22 may be placed in operation independently of the suction pressure so that the compressor 13 may be started even though defrosting of the evaporator 11 has not occurred. The switch arm 70 is maintained in engagement with the contact 71 for a predetermined number of cycles of operation of compressor 13 and then the switch arm 70 is moved out of engagement with the contact 71 so that the compressor cannot be started on its next cycle until the defrosting of the evaporator 11 has been accomplished.

The opening and closing of the switch formed by the switch arm 70 and the contact 71 is controlled by the momentary contact arrangement formed by the switch 26 and the contact 29 of the relay or starter 22 and a plurality of sequentially operated relays generally designated at 74, 75, 76, and 77. The relay 74 may comprise a relay coil 78 for operating switch arms 79, 80, and 81 with respect to contacts 82, 83, and 84. When the relay coil 78 is energized switch arms 79 and 81 are moved into engagement with contacts 82 and 84, respectively, and switch arm 80 is moved out of engagement with contact 83. The switch arms 79 and 80 are so arranged that they overlap in their action, that is, switch arm 79 engages contact 82 before switch arm 80 disengages contact 83. When the relay coil 78 is deenergized the switch arms 79 and 81 are moved out of engagement with their respective contacts 82 and 84 and the switch arm 80 is moved into engagement with contact 83 by means of springs gravity or other means, not shown. The relays 75 and 76 are exactly the same as the relay 74 and therefore like reference characters for the parts thereof have been utilized. However, in addition relay 76 operates switch arm 70 with respect to contact 71. Relay 77 may comprise a relay coil 86 for operating a switch arm 87 with respect to a contact 88. When the relay coil 86 is energized the switch arm 87 is moved out of engagement with the contact 88 and when the relay coil 86 is deenergized the switch arm 87 is moved into engagement with the contact 88 by means of springs gravity or other means, not shown. Power is supplied to the relays 74 to 77, inclusive, by means of a transformer 89 having a secondary 91 and a primary 90 connected across the line wires 66 and 67.

Assume now that the relays 74 to 77 are in the positions shown in the drawing and that the relay or starter 22 is deenergized. Upon a call for cooling by the box thermostat 32 the starter 22 is energized to place the compressor 13 in operation in the manner pointed out above. Since the switch arm 70 is engaging the contact 71 this can occur even though the evaporator 11 has not defrosted. Energization of the starter 78

or relay 22 causes the switch arm 26 to momentarily engage the contact 29 which completes a momentary circuit from the secondary 91 through contact 88 and switch arm 87 of relay 77, contact 29, switch arm 26 and contact 83, switch arm 80 and relay coil 78 of the relay 74 back to the secondary 91. Completion of this circuit energizes the relay coil 78 which moves the switch arm 79 into engagement with the contact 82 to complete a maintaining circuit for the relay coil 78 which may be traced from the secondary 91 through contact 88, switch arm 87 and contact 82, switch arm 79 and relay coil 78 of the relay 74 back to the secondary 91. This maintaining circuit for the relay coil 78 is completed before the momentary pull-in circuit thereof is broken by reason of the overlapping contact arrangement. The parts are so arranged that the switch arm 26 of the starter 22 disengages the contact 29 before the switch arm 81 of the relay 74 engages the contact 84. It follows then that when the starter 22 is energized to operate the compressor the first relay 74 is pulled in and is maintained in. When the call for cooling is satisfied the relay or starter 22 drops out to stop the compressor 13 but the switch arm 26 will not engage the contact 29 by reason of the piece of insulating material 30 carried by the contact 29. Hence no circuits are completed by the dropping out of the relay or starter 22.

Upon the next call for cooling by the box thermostat 32 the relay 22 is again energized to start the compressor 13 and to complete a momentary contact between the switch arm 26 and contact 29 of the relay 22. This momentary contact completes a momentary circuit from the secondary 91 through contact 88 and switch arm 87 of the relay 77, contact 29 and switch arm 26 of the starter 22, switch arm 81 and contact 84 of the relay 74, and contact 83, switch arm 80 and relay coil 78 of the relay 75 back to the secondary 91. Completion of this circuit energizes the relay coil 78 of the second relay 75 to move the switch arms 79 and 81 thereof into engagement with their respective contacts 82 and 84. Movement of the switch arm 79 into engagement with the contact 82 completes a maintaining circuit for the relay coil 78 of the relay 75 in the same manner as pointed out above for relay 74 and therefore the relay 75 is maintained in. Hence when the starter 22 is energized the second time to place the compressor 13 in operation the second relay 75 is pulled in and maintained in. The compressor continues to operate until the box temperature is satisfied whereupon the relay 22 is deenergized to stop the compressor 13.

The third time that the box thermostat calls for cooling to pull in the starter 22 the switch arm 26 again momentarily engages the contact 29 to complete a momentary circuit from the secondary 91 through contact 88 and switch arm 87 of relay coil 77, contact 29 and switch arm 26 of starter 22, switch arm 81 and contact 84 of relay 74, switch arm 81 and contact 83 of relay 75 and contact 83, switch arm 80 and relay coil 78 of the relay 76 back to the secondary 91. Completion of this circuit energizes the relay coil 78 of relay 76 to move the switch arms 79 and 81 thereof into engagement with the contacts 82 and 84 and to move the switch arms 80 and 70 out of engagement with the contact 83 and 71, respectively. Movement of the switch arm 79 into engagement with the contact 82

completes a maintaining circuit for the relay coil 78 of the relay 76 to maintain this relay in. Accordingly the third time that the compressor 13 is placed in operation the switch arm 78 is caused to disengage the contact 71. Since this breaks the shunt circuit around the electrodes 46 and 47 of the suction pressure controller 40, the relay or starter 22 then cannot be energized until the suction pressure has risen to 40 lbs. which is indicative of the defrosting of the evaporator 11 and until the box thermostat 32 calls for cooling.

When these two conditions exist, that is, high suction pressure and high box temperature, the relay or starter 22 is energized to start the compressor 13. Energization of the relay or starter 22 also causes momentary contact between switch arm 26 and the contact 29 to complete a circuit from the secondary 91 through contact 88 and switch arm 87 of relay 77, contact 29 and switch arm 26 of starter 22, switch arm 81 and contact 84 of relay 75, switch arm 81 and contact 84 of relay 76 and relay coil 86 of relay 77 back to the secondary 91. Completion of this circuit causes the switch arm 87 to disengage the contact 88 whereupon all of the circuits through the relays 74, 75, 76, and 77 are broken to drop these relays out. The parts are then returned to the positions shown in Figure 1, and hence requires a complete recycling of operation before defrosting of the evaporator 11 will again occur.

By reason of this arrangement the compressor 13 is placed in operation three times irrespective of the value of the suction pressure and the fourth time that the thermostat 32 requires operation of the compressor 13 the compressor cannot be operated until the evaporator coil 11 has defrosted. In other words, the compressor 13 will be cycled normally for three times and then will defrost on the fourth time. It is obvious that more relays may be interposed or less relays may be utilized so that the compressor could operate any number of times, say two times or eight times, before defrosting of the evaporator 11 is brought about.

Referring now to Figure 2 there is provided another arrangement for obtaining substantially the same results as are obtained in Figure 1, that is, periodic defrosting of a refrigerating apparatus. The same compressor 14 and space or box temperature responsive controller 32 have been utilized in Figure 2 and therefore like reference characters for these elements are set forth. Instead of utilizing the suction pressure controller 40, the high pressure cut-out 50 and the overload cut-out 60 of Figure 1, this form of the invention contemplates the use of a unitary control arrangement generally designated at 100 and which may be of the form shown and described in application Serial No. 196,447, filed by Albert L. Judson and Carl G. Kronmiller on March 17, 1938. This unitary control arrangement 100 is shown diagrammatically in Figure 2 to comprise a base or housing 101 in which is mounted a bellows 102 connected by a pipe 103 to the high pressure side of the refrigerating apparatus. The bellows 102 operates a lever 104 pivoted on a fulcrum member 105 against the action of a tension spring 106. One end of the tension spring 106 is connected to the lever 104 and the other end is connected to a nut 107 screw threadedly mounted on a screw 108. By rotating the screw 108 the pressure setting of the bellows 102 may be adjusted at will. The

lever 104 has adjustably mounted thereon an abutment member 109 having an abutment surface 110 for engaging a contact member 111 suitably anchored to a terminal 112. The contact member 111 carries a contact which engages a stationary contact terminal 113. The abutment member also has an abutment surface 114 for engaging a contact member 115 carried by a terminal 116. The contact member 115 carries a contact adapted to engage a contact post 117. Upon an increase in high pressure the abutment 114 first engages the contact member 115 to separate its associated contacts and then the abutment surface 110 engages the contact member 111 to separate its associated contacts. For purposes of illustration it is assumed that the contacts between contact member 115 and the contact post 117 make and break at 80 lbs. and that the contacts between the contact member 111 and the terminal contact 113 make and break at 180 lbs.

Also mounted in the casing 101 is a bellows 120 connected by a pipe 121 to the suction or pressure side of the refrigerating apparatus. The bellows 120 operates a lever 122 pivoted on a fulcrum member 123 against the action of a tension spring 124. One end of the tension spring 124 is connected to the lever 122 and the other end is connected to a nut 125 screw threadedly mounted on a screw 126. By suitably rotating the screw 126 the pressure setting of the bellows 120 may be adjusted. The lever 122 carries by means of an insulating pad 127 contacts 128 and 131 which are electrically coupled together. Contact 128 is adapted to engage a relatively stationary contact carried by a contact member 129 suitably anchored on a terminal 130. Contact 131 is adapted to engage a contact carried by a contact member 132 also suitably mounted on the terminal 116. Cams 133 and 134 are utilized for independently adjusting the positions of the contact members 129 and 130 with respect to the contacts 128 and 131, respectively. For purposes of illustration it is assumed that the cams 133 and 134 are so positioned the contact 128 engages and disengages the contact of the contact member 129 at substantially 15 lbs. and that the contact 131 engages and disengages the contact of the contact member 132 at substantially 40 lbs. As pointed out above a 40 lb. suction pressure occurs only after the evaporator has defrosted and accordingly contact 131 will not engage the contact member 132 until defrosting of the evaporator has been accomplished.

The various contacts of this unitary control arrangement 100 control the operation of a relay generally designated at 137 which also forms a part of this unitary control arrangement 100. This relay 137 may comprise a relay coil 138 for operating a bridge member 139 with respect to load contacts 140 and 141. The relay coil 138 also operates a bridge member 142 with respect to maintaining contacts 143 and 144. When the relay coil 138 is energized the bridge member 139 is moved into contact with the load contacts 140 and 141 and the bridge member 142 is moved into engagement with the maintaining contacts 143 and 144. When the relay coil 138 is deenergized the bridge members 139 and 142 are moved out of engagement with their respective contacts by means of springs gravity or other means, not shown.

The unitary control arrangement 100 also includes an overload cut-out generally designated at 146 which may comprise a casing 147 supporting a heater 148 which operates a bimetallic latch

arrangement, not shown, which in turn operates contacts 150 and 151. A lever 152 is utilized for resetting the overload cut-out after it has once been tripped by overload conditions. Upon the occurrence of overload conditions the heater 148 operates to trip the bimetallic latch mechanism to separate the contacts 150 and 151. After the contacts 150 and 151 are separated they may be reengaged by suitable manipulation of the lever 152.

The unitary control arrangement is also provided with a control terminal 153 which is electrically connected to the contact 143 and a power terminal 154. Since the above construction of the unitary control arrangement is fully shown in the above referred to Judson and Kronmiller application a further description of the construction thereof is not considered necessary.

Power is supplied to the compressor motor 14 and to the unitary control arrangement 100 by means of line wires 160 and 161 extending from a source of power, not shown, to terminal 149 of the overload cut-out 146 and load terminal 154, respectively. Wires 162 and 163 lead from the load terminal 154 and the contact terminal 141 to the compressor motor 14. Assume that the parts thus far described are in the position shown in Figure 2, the relay 137 is deenergized and hence the compressor motor 14 is not operating. As a result the suction pressure increases and the box temperature increases. When the suction pressure increases to a defrosting value of say 40 lbs., contact 131 engages contact member 132 and contact 128 engages contact member 129 and when the space temperature rises to 40° electrodes 37 and 38 are bridged to complete a starting circuit from the line wire 160 through contact terminal 113, contact member 111, terminal 112, electrodes 37 and 38 of the box temperature responsive controller 32, terminal 130, contact member 129, contacts 128 and 131, contact member 132, terminal 116, contact member 115, contact post 117, contact post 144, contacts 150 and 151 of the overload cut-out 146, relay coil 138 and terminal 154 back to the other line wire 161. Completion of this circuit energizes the relay coil 138 to cause the bridge member 139 to bridge the contacts 140 and 141 and to cause the bridge member 142 to bridge the contacts 143 and 144.

Bridging of the contacts 140 and 141 by the bridge member 139 completes a circuit from the line wire 160 through contact terminal 113, terminal 149, heater element 148, contact 148, bridge member 139, contact 141, wire 163, compressor motor 14, wire 162, and terminal 154 back to the other line wire 161. The compressor 14 is accordingly placed in operation.

Movement of the bridge member 142 into engagement with the contacts 143 and 144 completes a maintaining circuit for the relay coil 138 independently of the contact members 115 and 132 which may be traced from the line wire 160 through contact posts 113, contact member 111, terminal 112, electrodes 37 and 38 of the box temperature responsive controller 132, terminal 130, contact member 129, contact 128, contact post 143, bridge member 142, contact post 144, contacts 150 and 151 of the overload cut-out 146, relay coil 138 and terminal 154 back to the other line wire 161. Completion of this circuit maintains the relay coil 138 energized until the box thermostat 32 is satisfied or until the suction pressure is pumped down to 15 lbs. or until the high pressure rises to 180 lbs. Likewise an over-

load condition will cause shutting down of the compressor.

Summing up briefly the relay 137 is energized to cause operation of the compressor only when the box temperature rises to 40°, the suction pressure rises to a defrosting value of 40 lbs. and the high pressure decreases to a predetermined low value of 80 lbs. After these conditions have been established and the compressor is placed in operation it is maintained in operation even though the suction pressure is decreased and the high pressure is increased until the space or box temperature decreases to 38° or unless the suction pressure should decrease to a predetermined low value of 15 lbs. or the high pressure should increase to a predetermined high value of 180 lbs. By reason of this arrangement the compressor cannot be placed in operation until defrosting has occurred and until the high pressure decreases to a predetermined low value which provides a minimum starting torque for the compressor motor.

Provision is made in this modification for allowing the compressor to be started a predetermined number of times without defrosting as in the previous modification and the mechanism for accomplishing this in Figure 2 is generally designated at 164. This mechanism may comprise an electromagnet or solenoid 165 preferably connected in parallel with the compressor motor 14. The solenoid 165, when energized, attracts an armature 166 against the action of a spring 167 and when the solenoid 165 is deenergized the spring 167 moves the armature 166 to the position shown in Figure 2. The armature 166 is connected to an arm 168 pivotally mounted at 169. The arm 168 carries a pawl 170 which engages a ratchet wheel 171 which may also be pivoted at 169. The ratchet wheel is rigidly secured to a gear 172. When the solenoid or electromagnet 175 is energized the pawl 170 rotates the ratchet wheel 171 and the gear 172 in a counter-clockwise direction and the ratchet wheel and gear 172 may be held in this position by means of a stationary pawl 173. The gear 172 meshes with a gear 174 pivoted at 175. The gear 174 carries an arm 176 which is adapted to slide on a conducting track 177 which is provided with diametrically opposed insulating buttons 178 and 179 which are also adapted to be engaged by the slider 176. Counter-clockwise rotation of the gear 172 in the manner pointed out above causes clockwise rotation of the gear 174. Hence every time that the compressor motor 14 is operated the slider 176 is inched along in a clockwise direction. The conducting track 177 is connected to the terminal 153 of the unitary control arrangement 100 and the slider 176 is connected to the terminal 116 which supports the contact members 115 and 132.

When the slider 176 is engaging the insulating button 178 as shown in Figure 2 or is engaging the insulating button 179 the mechanism 164 has no effect upon the operation of the unitary control arrangement 100 and when the parts are in this position the unitary control arrangement 100 acts in conjunction with the box thermostat 32 to give a defrosting control in the manner outlined above. However, when the slider 176 engages the conducting tract 177 contact 131 and contact member 132 are shunted out of the starting circuit for the relay 137 whereupon the compressor can be placed in operation even though the suction pressure has not risen to the defrosting value of 40 lbs. This auxiliary start-

ing circuit for the relay 177 which shunts out contact 131 and contact member 132 to start the compressor motor 14 may be traced from the line wire 160 through contact terminal 113, contact member 111, terminal 112, electrodes 37 and 38, terminal 130, contact member 129, contact 128, contact post 143, terminal 153, conducting track 177, slider 176, terminal 116, contact member 115, contact post 117, contact post 144, contacts 150 and 151 of the overload cut-out 146, relay coil 137, and terminal 154 back to the other line wire 161. Completion of this circuit energizes the relay 137 to cause operation of the compressor motor 14 and to complete the above referred to maintaining circuit for the relay coil 138.

Accordingly when the slider 176 is engaging the conducting track 177 the low pressure cut-in switch formed by the contact 131 and the contact member 132 is shunted out or rendered inoperative to allow the compressor motor 14 to be placed in operation even though the suction pressure has not risen to 40 lbs. Since the slider 176 is inched in a clockwise direction every time the compressor motor 14 is placed in operation the slider 176 will eventually engage one of the insulating buttons 178 or 179 at which time this shunt circuit is broken whereupon defrosting of the evaporator must be brought about before the compressor motor 14 may again be started. The mechanism 164 may be adjusted either by changing the gear ratio between the gears 172 and 174 or by changing the number of ratchet teeth picked up by the pawl 170 to vary the number of cycles of operation of the compressor that may be obtained before the evaporator is caused to be defrosted.

From the above it is seen that I have provided a control arrangement for a refrigerating apparatus wherein the refrigerating apparatus is started and stopped to maintain desired conditions such as temperature conditions in a box or space, wherein means responsive to a condition which is a measure of defrosting of the evaporator are provided for preventing starting of the refrigerating apparatus until defrosting of the evaporator has occurred and wherein means are provided for rendering this last mentioned means operative and inoperative for defrosting the evaporator following a predetermined number of cycles of operation of the refrigerating apparatus.

Although for purposes of illustration two forms of this invention have been disclosed other forms thereof may become apparent to those skilled in the art upon reference to this disclosure and therefore this invention is to be limited only by the scope of the appended claims and prior art.

I claim as my invention:

1. In a mechanical refrigerating system having a compressor and an evaporator for maintaining desired conditions, the combination of, means responsive to changes in the condition being maintained to start and stop the compressor for maintaining desired conditions, means responsive to a condition which is a measure of defrosting of the evaporator to prevent the first responsive means from starting the compressor until defrosting of the evaporator has been established, and means controlled by the operation of the compressor to render said second responsive means inoperative for a predetermined number of compressor operations and then rendering said second responsive means operative whereby the evaporator is defrosted

- after the compressor has operated a predetermined number of times.
2. In a mechanical refrigerating system having a compressor and an evaporator for maintaining desired conditions, the combination of, means responsive to changes in the condition being maintained to start and stop the compressor for maintaining desired conditions, means responsive to suction pressure for preventing the first responsive means from starting the compressor until the suction pressure has risen sufficiently to defrost the evaporator, and means controlled by the operation of the compressor to render said second responsive means inoperative for a predetermined number of compressor operations and then rendering said second responsive means operative whereby the evaporator is defrosted after the compressor has operated a predetermined number of times.
3. In a mechanical refrigerating system having a compressor and an evaporator for maintaining desired conditions, the combination of, means responsive to changes in the condition being maintained to start and stop the compressor for maintaining desired conditions, means responsive to a condition which is a measure of defrosting of the evaporator to prevent the first responsive means from starting the compressor until defrosting of the evaporator has been established, means to render normally said second responsive means inoperative whereby the compressor is controlled by the first responsive means without defrosting of the evaporator, and means operative as an incident to a predetermined number of cycles of operation of the compressor for rendering said last mentioned means inoperative whereby the evaporator is defrosted.
4. In a mechanical refrigerating system having a compressor and an evaporator for maintaining desired conditions, the combination of, means responsive to changes in the condition being maintained to start and stop the compressor for maintaining desired conditions, means responsive to suction pressure for preventing the first responsive means from starting the compressor until the suction pressure has risen sufficiently to defrost the evaporator, means to render normally said second responsive means inoperative whereby the compressor is controlled by the first responsive means without defrosting of the evaporator, and means operative as an incident to a predetermined number of cycles of operation of the compressor for rendering said last mentioned means inoperative whereby the evaporator is defrosted.
5. In a mechanical refrigerating system having an electrically operated compressor and an evaporator for maintaining desired conditions, the combination of, a starter for the compressor including an operating coil, a load switch for the compressor and a maintaining switch, first switching means, means responsive to variations in the condition being maintained to close the first switching means when operation of the compressor is required to maintain the desired condition, second switching means, means responsive to a condition which is a measure of defrosting of the evaporator for closing the second switching means when the evaporator is defrosted, a starting circuit for the starter including the first and second switching means and the operating coil for operating the compressor when both switching means are closed, a maintaining circuit for the starter including the first switching means, the maintaining switch and the operating coil for maintaining the compressor in operation after it has started, third switching means, an auxiliary starting circuit for the starter including the first and third switching means and the operating coil for starting the compressor when both switching means are closed, and means operated as an incident to operation of the compressor for maintaining the third switching means closed for a predetermined number of cycles of the compressor and then opening the same.
6. In a mechanical refrigerating system having an electrically operated compressor and an evaporator for maintaining desired conditions, the combination of, a starter for the compressor including an operating coil, a load switch for the compressor and a maintaining switch, first switching means, means responsive to variations in the condition being maintained to close the first switching means when operation of the compressor is required to maintain the desired condition, second switching means, means responsive to a condition which is a measure of defrosting of the evaporator for closing the second switching means when the evaporator is defrosted, a starting circuit for the starter including the first and second switching means and the operating coil for operating the compressor when both switching means are closed, a maintaining circuit for the starter including the first switching means, the maintaining switch and the operating coil for maintaining the compressor in operation after it has started, third switching means, an auxiliary starting circuit for the starter including the first and third switching means and the operating coil for starting the compressor when both switching means are closed, means for normally maintaining the third switching means closed, and means for opening the third switching means every time that the compressor has operated a predetermined number of times.
7. In a mechanical refrigerating system having an electrically operated compressor and an evaporator for maintaining desired conditions, the combination of, a starter for the compressor including an operating coil, a load switch for the compressor and a maintaining switch, first switching means, means responsive to variations in the condition being maintained to close the first switching means when operation of the compressor is required to maintain the desired condition, second switching means, means responsive to suction pressure for closing the second switching means when the suction pressure has risen sufficiently to defrost the evaporator, a starting circuit for the starter including the first and second switching means and the operating coil for operating the compressor when both switching means are closed, a maintaining circuit for the starter including the first switching means, the maintaining switch and the operating coil for maintaining the compressor in operation after it has started, third switching means, an auxiliary starting circuit for the starter including the first and third switching means and the operating coil for starting the compressor when both switching means are closed, and means operated as an incident to operation of the compressor for maintaining the third switching means closed for a predetermined number of cycles of the compressor and then opening the same.
8. In a mechanical refrigerating system having an electrically operated compressor and an evap-

operator for maintaining desired conditions, the combination of, first switching means, means responsive to variations in the condition being maintained to close the first switching means when operation of the compressor is required to maintain the desired condition, second switching means, means responsive to a condition which is a measure of defrosting of the evaporator for closing the second switching means when the evaporator is defrosted, a control circuit for the compressor including both of said switching means to operate the compressor when both switches are closed whereby defrosting of the evaporator is required before the compressor is operated by this circuit, third switching means, a second control circuit for the compressor including the first and third switching means to operate the compressor when both switches are closed whereby the compressor is operated by this circuit without defrosting, and means operated as an incident to operation of the compressor for opening and closing the third switching means for defrosting the evaporator at intervals.

9. In a mechanical refrigerating system having an electrically operated compressor and an evaporator for maintaining desired conditions, the combination of, first switching means, means responsive to variations in the condition being maintained to close the first switching means when operation of the compressor is required to maintain the desired condition, second switching means, means responsive to variations in suction pressure for closing the second switching means when the suction pressure has risen sufficiently to cause defrosting of the evaporator, a control circuit for the compressor including both of said switching means to operate the compressor when both switches are closed whereby defrosting of the evaporator is required before the compressor is operated by this circuit, third switching means, a second control circuit for the compressor including the first and third switching means to operate the compressor when both switches are closed whereby the compressor is operated by this circuit without defrosting, and means operated as an incident to operation of the compressor for opening and closing the third switching means for defrosting the evaporator at intervals.

10. In a mechanical refrigerating system having an electrically operated compressor and an evaporator for maintaining desired conditions, the combination of, first switching means, means responsive to variations in the condition being maintained to close the first switching means when operation of the compressor is required to maintain the desired condition, second switching means, means responsive to a condition which is a measure of defrosting of the evaporator for closing the second switching means when the evaporator is defrosted, a control circuit for the compressor including both of said switching means to operate the compressor when both switches are closed whereby defrosting of the evaporator is required before the compressor is operated by this circuit, third switching means, a second control circuit for the compressor including the first and third switching means to operate the compressor when both switches are closed whereby the compressor is operated by this circuit without defrosting, and means operated as an incident to operation of the compressor for opening and closing the third switching means for defrosting the evaporator at intervals, said last named means including, a switch closed momentarily upon starting of

the compressor, a plurality of relays, one of said relays operating said third switching means, and means controlled by said momentarily closed switch for operating said relays in sequence.

11. In a mechanical refrigerating system having an electrically operated compressor and an evaporator for maintaining desired conditions, the combination of, first switching means, means responsive to variations in the condition being maintained to close the first switching means when operation of the compressor is required to maintain the desired condition, second switching means, means responsive to variations in suction pressure for closing the second switching means when the suction pressure has risen sufficiently to cause defrosting of the evaporator, a control circuit for the compressor including both of said switching means to operate the compressor when both switches are closed whereby defrosting of the evaporator is required before the compressor is operated by this circuit, third switching means, a second control circuit for the compressor including the first and third switching means to operate the compressor when both switches are closed whereby the compressor is operated by this circuit without defrosting, means operated as an incident to operation of the compressor for opening and closing the third switching means for defrosting the evaporator at intervals, said last named means including, a switch closed momentarily upon starting of the compressor, a plurality of relays, one of said relays operating said third switching means, and means controlled by said momentarily closed switch for operating said relays in sequence.

12. In a mechanical refrigerating system having an electrically operated compressor and an evaporator for maintaining desired conditions, the combination of, first switching means, means responsive to variations in the condition being maintained to close the first switching means when operation of the compressor is required to maintain the desired condition, second switching means, means responsive to a condition which is a measure of defrosting of the evaporator for closing the second switching means when the evaporator is defrosted, a control circuit for the compressor including both of said switching means to operate the compressor when both switches are closed whereby defrosting of the evaporator is required before the compressor is operated by this circuit, third switching means, a second control circuit for the compressor including the first and third switching means to operate the compressor when both switches are closed whereby the compressor is operated by this circuit without defrosting, means operated as an incident to operation of the compressor for opening and closing the third switching means for defrosting the evaporator at intervals, said last named means including, an electromagnet energized when the compressor is operated and a pawl and ratchet arrangement operated by said electromagnet for operating said third switching means.

13. In a mechanical refrigerating system having an electrically operated compressor and an evaporator for maintaining desired conditions, the combination of, first switching means, means responsive to variations in the condition being maintained to close the first switching means when operation of the compressor is required to maintain the desired condition, second switching means, means responsive to variations in suction pressure for closing the second switching means when the suction pressure has risen sufficiently to cause defrosting of the evaporator, a control circuit

- cuit for the compressor including both of said switching means to operate the compressor when both switches are closed whereby defrosting of the evaporator is required before the compressor is operated by this circuit, third switching means, a second control circuit for the compressor including the first and third switching means to operate the compressor when both switches are closed whereby the compressor is operated by this circuit without defrosting, means operated as an incident to operation of the compressor for opening and closing the third switching means for defrosting the evaporator at intervals, said last named means including, an electromagnet energized when the compressor is operated and a pawl and ratchet arrangement operated by said electromagnet for operating said third switching means.
14. In combination, a plurality of relays having operating coils, maintaining switches and transfer switches, a momentary contact switch, means for completing a starting circuit for the operating coil of a first relay to pull in the same including the momentary contact switch, means for completing a maintaining circuit for the operating coil of the first relay to maintain the same pulled in including the maintaining switch thereof, means for completing a starting circuit for the operating coil of another relay to pull in the same

including the momentary contact switch and the transfer switch of the first relay, and means for completing a maintaining circuit for the operating coil of the other relay to maintain the same pulled in the maintaining switch thereof.

15. In combination, a plurality of relays having operating coils, maintaining switches and transfer switches, a momentary contact switch, means for completing a starting circuit for the operating coil of a first relay to pull in the same including the momentary contact switch, means for completing a maintaining circuit for the operating coil of the first relay to maintain the same pulled in including the maintaining switch thereof, means for completing a stationary circuit for the operating coil of another relay to pull in the same including the momentary contact switch and the transfer switch of the first relay, means for completing a maintaining circuit for the operating coil of the other relay to maintain the same pulled in the maintaining switch thereof, a relay for dropping out all of the relays when pulled in including an operating coil, and means for completing a circuit to the operating coil of said last mentioned relay including the momentary contact switch and the transfer switches of said plurality of relays.

WILLIAM L. McGRATH.
